UNITED STATES PATENT OFFICE.

ANTHONY HORTON BLISS, OF NORTH ATTLEBORO, MASSACHUSETTS.

BRACELET.

No. 823,024.

Specification of Letters Patent.

Patented June 12, 1906.

Application filed February 23, 1906. Serial No. 302,412.

To all whom it may concern:

Be it known that I, ANTHONY HORTON BLISS, a citizen of the United States, residing at North Attleboro, in the county of Bristol 5 and Commonwealth of Massachusetts, have invented certain new and useful Improvements in Bracelets, of which the following is a specification.

This invention relates to an improvement 10 in flexible bracelets or articles of a similar nature made up of individual link members which are joined together in such a manner as to permit their separation and allow the expansion and contraction of the article as 15 its use may require.

It is the object of the present invention to provide a series of individual link members with a connecting means which will be flexible and capable of ready adaptation to the 20 relative movements of the different parts and at the same time to be of such parts as will assure simplicity of structure and certainty of operation and have the strength to withstand the uses to which such an article is put. 25 To this end I have devised a certain combination of link members, connecting bars, and springs which I will describe more fully in the specification which follows and which are shown in the drawings which form a part 30 thereof.

In the drawings, Figure 1 indicates four connected links of my invention; Fig. 2, a central longitudinal section of a link-shell; Fig. 3, a side view of the stud-plate; Fig. 4, a 35 plan view of the same, and Fig. 5 a view of the coupling-rod with the spring in place.

1 represents the body portions, and 2 the caps, of the unit members which go to make up the links of my invention.

40 11 represents openings arranged in pairs on the opposite side of the body portions 1. In these units are set stud-plates 3, which rest in the bottom thereof and are held therein by clips 4, which are turned up from the plate 45 and press against the walls of the link-body.

5 is a stud turned up on the plate 3 a little to one side of its central point.

6 is a bar having its ends turned at right angles to form coupling-rods 7, and 8 represents hooks formed on the ends of said rods. 50 9 is a spiral spring which connects the ends of said rods 7 and has its ends engaged with the hooks 8.

In assembling the parts the plate 3 is 55 forced into the body portion 1 of the link with its clips 4 in engagement with the sides

of the body portion, so that the plate will be held firmly in place. The body portions are then placed side by side in a series and the bar 6, fitted with its spiral spring 9, is dropped 60 into one link, with the rods 7 extending through the adjacent openings 11 and with the spiral spring 9 passed over the stud 5 of the plate, as shown in the drawings. The stud thus supports the spring 9 and gives it a 65 rest over which it is bent like a bow when the links are separated. The tendency of the spring is to assume a position in a straight line, and therefore to draw the ends of the rods 7 up into alinement with the fixed stud 70 5, and thus to keep the links held together. After the links have been all connected together by the coupling-rods and springs the caps 2 are placed on the links and the links finished off.

In normal position with the links together the springs 9 assume the position shown in the link on the right of Fig. 1, in which it appears as drawn straight between the hooks 8. When the links are separated, the springs are 80 bent over the stud 5 as the rods 7 are drawn down, and in this position it assumes the form shown in the next link to the left of the one last mentioned.

What I therefore claim, and desire to secure by Letters Patent, is—

1. In a device of the class described, the combination of adjacent hollow link members, a pair of openings in the sides of each link member, a bar in each link member having its ends bent to form coupling-rods which extend through the adjacent openings into the next link member, a spiral spring connecting the ends of said bar and means for supporting said spring centrally therebetween. 95

2. In a device of the class described, the combination of adjacent link members, openings in the sides of each link member, a pair of coupling-rods extending from each link member and entering the adjacent openings 100 in the next link member, and a spiral spring connecting the ends of said rods and supported centrally therebetween.

3. In a device of the class described, the combination of adjacent hollow link members, a pair of openings on opposite sides of each member, a bar in each member having its ends bent to form coupling-rods which extend through the openings into the next link member, a spiral spring engaging the 105 ends of said bars and a plate in the link member having a projection thereon to support

said spiral spring centrally between the ends of the rod.

4. In a device of the class described, the combination of adjacent hollow link members, a pair of openings on opposite sides of each member, a bar in each member having its ends bent to form coupling-rods which extend through said openings, links on the ends of said rods, a spiral spring connecting

10
said hooks and a projection in the link member for supporting said spiral spring centrally between the ends of the bar.

In testimony whereof I affix my signature in presence of two witnesses.

ANTHONY HORTON BLISS.
